US00D939490S

(12) **United States Design Patent** (10) **Patent No.:** **US D939,490 S**
(45) **Date of Patent:** **** Dec. 28, 2021**

(54) **CASE FOR MOBILE PHONE**

(71) Applicant: **Samsung Electronics Co., Ltd.**, Suwon-si (KR)

(72) Inventors: **Eunsoo Kim**, Seongnam-si (KR); **Taeho Kim**, Yongin-si (KR); **Byoungjin Kim**, Seoul (KR); **Junyong Song**, Seongnam-si (KR)

(73) Assignee: **SAMSUNG ELECTRONICS CO., LTD.**, Suwon-si (KR)

(**) Term: **15 Years**

(21) Appl. No.: **29/668,548**

(22) Filed: **Oct. 31, 2018**

(30) **Foreign Application Priority Data**

May 4, 2018 (KR) 30-2018-0020866

(51) **LOC (13) Cl.** **14-03**

(57) **CLAIM**

The ornamental design for a case for mobile phone, as shown and described.

DESCRIPTION

FIG. 1 is a front perspective view of a case for mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The evenly-spaced dashed broken lines in the figures depict portions of the case for mobile phone that form no part of the claimed design.

1 Claim, 8 Drawing Sheets
